UNITED STATES PATENT OFFICE.

WALTER C. BECKWITH, OF NORWALK, OHIO.

VELOCIPED.

SPECIFICATION forming part of Letters Patent No. 256,870, dated April 25, 1882.

Application filed July 23, 1881. (No model.)

To all whom it may concern:

Be it known that I, WALTER C. BECKWITH, of Norwalk, in the county of Huron and State of Ohio, have invented certain new and useful Improvements in Velocipedes; and I do hereby declare the following to be a full, clear, and exact description of the invention, such as will enable others skilled in the art to which it pertains to make and use it, reference being had to the accompanying drawings, which form part of this specification.

My invention relates to velocipedes, and particularly to that class of velocipedes known as "tricycles" or "three-wheeled velocipedes," and it consists in parts and combination of parts that will be more fully hereinafter described and claimed.

In the drawings, Figure 1 is an isometric view of a velocipede constructed according to my invention. Fig. 2 is a detached view of that portion of my device which shows the steering mechanism. Fig. 3 is a view in detail of a modification of the driving mechanism.

In the said drawings, A represents the seat, which is intended to be occupied by the operator. This seat has suitable supports, A', which rest upon the axle B and sustain the rear portion of the seat. To the forward portion is attached a leg, C, which is sustained by the shank D of the caster-wheel E. To the leg C is adjustably attached the cross-piece F, which is provided with foot-rests G. To permit a vertical adjustment of this cross-piece, and so regulate the foot-rest G for the convenience of the size of the person operating the velocipede, the leg C is slotted and provided with a set-screw to hold it at any desired point in the slot. This cross-piece F is pivoted at F'.

H H are pulleys attached to the under side of the seat A, and over which pass the straps I I. The axle B is provided with two cranks, B' and B''. These cranks are connected with and operated by the cross-bar F by means of the straps I. The shank D of the caster-wheel E is pivoted to the leg C, as shown in Fig. 2, by means of brackets or supports d. At its upper end it is provided with a crank, D'. To this crank D' is pivoted a cross-bar, K. To either end of this cross-bar K are attached levers L L, pivoted to brackets M upon the side of the seat A, and provided at either upper extremity with handles N N.

In Fig. 3 is shown a modification of the driving mechanism of my device. As shown in Fig.

1, in this modification the strap I, extending from the cross-bar F, is attached to a bell-crank, P, suspended from the seat A. To the other end of the bell-crank is attached a rigid bar connecting the same with the cranks B' 60 and B'' in the axle B.

Having thus described the construction of my device, its operation is as follows: The person who desires to operate this device will occupy the seat A, placing his feet upon the rests G G, and moving his feet forward and backward alternately, which will operate the straps I, which are connected to the cranks B' B'' of the axle B, and thus drive the velocipede forward or backward, as desired. If it is desired 70 to keep a straight forward course, the caster-wheel E will be kept moving in a parallel plane to that of the main wheels O O. If it is desired to turn to the right or to the left, the wheel E can be easily turned in the direction desired 75 by manipulating the handles N N, which are convenient for operation to the person occupying the seat A.

It is apparent that two wheels may be substituted for the single caster-wheel E without 80 departing from my invention.

What I claim is—

1. In a three-wheeled vehicle or velocipede, the combination, with a double-crank axle and the leg connecting the front or caster wheel 85 and the seat, of an adjustable oscillating foot-rest and straps, or equivalent means, connecting the cranks and the outer ends of said foot-rest, substantially as set forth.

2. In a velocipede, the combination, with the 90 leg C, of the centrally-pivoted rest F, constructed and arranged substantially as described, to be vertically adjusted, substantially as set forth.

3. In a three-wheeled velocipede, the combination of a caster-wheel, E, having its shank pivoted to the leg C, the crank D', and suitable mechanism for moving said crank, substantially as and for the purposes shown. 95

4. In a velocipede adapted to be driven by 100 the feet, the combination, with a leg supported by a caster-wheel, of a bar adjustably attached to the leg, substantially as and for the purposes shown.

In testimony whereof I have signed my name 105 to this specification in the presence of two subscribing witnesses.

Witnesses: WALTER C. BECKWITH,
ARTHUR L. HUSTED,
C. L. KENNAN.
